UNITED STATES PATENT OFFICE

2,641,686

ROTATABLE ELECTRICAL MARKER LIGHT
FOR TRAINS

Alfred B. Carruthers, Fort Scott, Kans.

Application January 11, 1951, Serial No. 205,570

2 Claims. (Cl. 240—24)

1

This invention comprises novel and useful improvements in lamps, and more particularly pertains to electrical train markers.

An important object of this invention is to provide an improved mounting for a train marker whereby the marker may be angularly adjustably positioned in various predetermined positions to display the correct signals.

Another object of this invention is to provide a marker light for trains, and mounting means therefor which is of simple and compact construction, and which is well adapted for the purposes intended.

An important feature of this invention resides in the provision of a marker light for trains including a housing having an upwardly extending spindle thereon, an arm which journals the spindle, a plunger reciprocably carried by the arm and movable into and out of an apertured collar on the spindle, together with an actuator finger pivotally attached to the plunger and overlying the end of the spindle which constitutes a fulcrum therefor as the finger is moved into position to cause the plunger to move out of engagement with the apertured collar.

Another feature of this invention resides in the provision of a marker light for trains, in accordance with the foregoing feature, together with an improved means for housing the plunger biasing spring on the support arm.

A further feature of this invention resides in the provision of a signal light, in accordance with the foregoing features, with the lamp socket carried by the undersurface of the top of the housing, and a hinged bottom for the housing, to facilitate changing of the lamp.

These, together with various ancillary objects and features are attained by this device, a preferred embodiment of which is illustrated in the accompanying drawings wherein:

Figure 1 is a side elevational view of the marker;

Figure 2 is a top plan view of the marker;

Figure 3 is a vertical sectional view taken on the plane 3—3 of Figure 2;

Figure 4 is a fragmentary side elevational view of the marker and support arm, parts being broken away and shown in section to illustrate details of construction;

Figure 5 is a fragmentary horizontal sectional view taken on the plane 5—5 of Figure 4; and,

Figure 6 is a fragmentary horizontal sectional view, taken on the plane 6—6 of Figure 3.

Reference is now made more specifically to the accompanying drawings wherein the marker

2

light for trains denoted generally by the numeral 10 is illustrated, and which marker includes a housing 12 and support arm 14.

The housing 12, as is apparent from the drawings, is dome-shaped, and has an open bottom which is reinforced by the rolled edge 16. A bottom 18 having an upstanding peripheral rim 20 is swingably attached to the housing as by hinge 22, a suitable latch (not shown) being provided on the bottom to frictionally engage the rolled edge 16, and retain the cover in its closed position. Suitable supporting legs 24 may be provided for use when the lamp is not attached to the support arm. The housing is provided with openings 26 having inwardly directed retaining flanges 28 about the periphery thereof, and suitable lenses 30 are positioned in the opening. Clamps 32 are attached to the casing as by fasteners 34 and engage the proximate edges of adjacent lenses to retain the latter in position in their respective openings.

The upper end of the housing is provided with an integral ferrule 36 which receives the externally threaded lower end 38 of the spindle 40. A locking collar 42 is threadedly attached to the end 38 of the spindle and engages the ferrule 36 to retain the housing on the spindle, a suitable set screw 44 being provided to prevent relative rotation between the housing and spindle. The base 46 of the lamp socket 48 is secured to the housing 12 by fasteners 50, and underlies the inner end of the spindle. A lamp 52 is disposed in the socket 48, and conductors 54 lead to a female socket 56 carried by the housing. As is conventional, a cooperating plug member 58 is detachably mounted in the socket and connects the conductors 60, which lead to the source of power (not shown), to the conductors 54.

An integral flange 62 is carried by the spindle 40 and overlies the upper end of the ferrule 36, the spindle also being formed with an intermediate portion 64, contiguous with the flange 62.

The support arm 14 is longitudinally curved and is provided with a mounting flange 66 on one end thereof, and an integral sleeve 68 on the other end thereof. The spindle 40 extends through the sleeve 68 with the intermediate portion 64 abutting the lower end of the sleeve, and a fastener 70, threadedly attached to the upper end of the spindle, abutting the upper end of the sleeve. A collar 72 is non-rotatably attached to the intermediate portion 64 of the spindle, by a set screw 74, and a plurality of circumferentially spaced bores 76 are formed

in the collar for the reception of the locking plunger 78. The plunger is reciprocably received in a bore 80 in the flange 82 which is formed integral with the sleeve, and which overlies the collar 72.

A casing 84 having mounting ears 86, formed integrally therewith, is attached to the sleeve 68 by fasteners 88 with the open end of the casing abutting the flange 82 in registry with the bore 80 therein. As is best shown in Figure 4, the plunger 78 extends through the top wall 90 of the casing, and a spring 92 is guidably disposed about the plunger within the casing, and terminally abuts the top wall of the casing and the collar 94 on the plunger to yieldingly bias the plunger into one of the bores 76 in the collar 72.

An actuating finger 96 is provided with a pair of spaced depending tabs 98 at its forward end, which tabs are pivotally attached to the plunger by a pin 100. The intermediate portion of the finger overlies the end of the spindle 40 and fastener 70 whereby they constitute a fulcrum for the finger, as the latter is pivoted to urge the plunger 78 out of the bores 76. A pair of spaced ears 102 are also carried by the finger 96, which ears are provided with slots 104 for the reception of the pins 106 carried by the arm 14. It is contemplated that the pins 106 limit upward pivotal movement of the finger so that the spring 92 will serve to yieldingly urge the finger into engagement with the spindle 40 and fastener 70, to prevent rattling of the finger. It is contemplated, however, that the slot 104 be so shaped as to permit plunger withdrawing movement of the finger 96. As will be appreciated, the plunger constrains movement of the tabs 98 and pin 100 in a vertical path, and consequently the finger 96 is disposed in sliding pivotal engagement with the spindle.

From the foregoing it will be appreciated that the housing 12 may be set in any predetermined angularly disposed position by merely depressing the finger 96 which fulcrums about the end of the spindle 40 and retracts the plunger, permitting the housing to be rotated to any selected position. The finger is then released and the spring 92 urges the plunger into position in one of the bores 76 in the collar, thereby locking the housing against rotation.

Having described the invention, what is claimed as new is:

1. A marker light for trains comprising a casing including a dome shaped top wall, an integral ferrule on said dome, a spindle including a threaded end extending through said ferrule, a flange carried by said spindle over-

lying the end of said ferrule, a threaded locking collar threadedly engaging the threaded end of said spindle, said ferrule being non-rotatably secured between said flange and said locking collar, an intermediate portion on said spindle, a collar non-rotatably attached to said intermediate portion of said spindle, a support arm, a sleeve on said arm, said spindle extending through said sleeve with the intermediate portion abutting said sleeve, a plurality of circumferentially spaced parallel bores extending longitudinally in said collar, a flange on said sleeve, said flange having a bore alignable with the bores of said collar, a plunger mounted on said sleeve and extending through the bore of said flange, said plunger being selectively engageable in the bores of said collar.

2. A marker light for trains comprising a casing including a dome shaped top wall, an integral ferrule on said dome, a spindle including a threaded end extending through said ferrule, a flange carried by said spindle overlying the end of said ferrule, a threaded locking collar threadedly engaging the threaded end of said spindle, said ferrule being non-rotatably secured between said flange and said locking collar, an intermediate portion on said spindle, a collar non-rotatably attached to said intermediate portion of said spindle, a support arm, a sleeve on said arm, said spindle extending through said sleeve with the intermediate portion abutting said sleeve, a plurality of circumferentially spaced parallel bores extending longitudinally in said collar, a flange on said sleeve, said flange having a bore alignable with the bores of said collar, a plunger mounted on said sleeve and extending through the bore of said flange, said plunger being selectively engageable in the bores of said collar, resilient means yieldingly biasing said plunger into the selected one of the bores in said collar, an actuating finger pivotally secured to the plunger, said finger extending across the end of the spindle, an ear carried by said finger, said ear having a slot therein, a pin carried by the arm, said slot engaging said pin to limit movement of said finger.

ALFRED B. CARRUTHERS.
